United States Patent Office

Des. 217,244

Patented Apr. 21, 1970

217,244

BUILDING BLOCK

Robert C. Fairfield, Toronto, Ontario, Canada, assignor
to Dufair Limited, Toronto, Ontario, Canada, a cor-
poration of Canada

Filed Jan. 24, 1969, Ser. No. 15,494

Term of patent 14 years

Int. Cl. D25—01

U.S. Cl. D18—2

FIG. 1

FIG. 2

FIG. 1 is a front perspective view taken from above of
a building block embodying my new design; and
FIG. 2 is a rear perspective view taken from below of
the said building block.

I claim:

The ornamental design for a building block, as shown.
